UNITED STATES PATENT OFFICE.

AUGUST STILKE, OF BUFFALO, NEW YORK.

RAIL-TIE FASTENER.

1,026,373.

Specification of Letters Patent. Patented May 14, 1912.

Application filed November 8, 1911. Serial No. 659,179.

To all whom it may concern:

Be it known that I, AUGUST STILKE, a citizen of the United States, residing at Buffalo, in the county of Erie and State of 5 New York, have invented new and useful Improvements in Rail-Tie Fasteners, of which the following is a specification.

This invention relates to a fastener for securing the rails to the ties of a railway.

10 The object of this invention is to produce a simple and inexpensive fastener of this character which serves not only as a means for securing a rail to a tie but also serves as a tie plate to prevent undue wearing of the 15 tie and which can be readily applied to the tie and rail when building the railway and also removed therefrom when making repairs.

In the accompanying drawings: Figure 20 1 is a vertical cross section of my improved fastener applied to a rail and tie. Fig. 2 is a horizontal section of the same, on a reduced scale, in line 2—2, Fig. 1. Figs. 3 and 4 are detached perspective views of the 25 tie plate and locking plate, respectively.

Similar characters of reference indicate corresponding parts throughout the several views.

1 represents a railway tie which is 30 constructed of wood as usual and which is arranged crosswise underneath the rail 2 of the railway.

My improved fastener for securing the rail to the tie comprises generally a tie 35 plate 3, a locking plate 4 and a plurality of screws 5, 6 or equivalent means.

The plate preferably has a flat underside which engages with the upper side of the tie. On its upper side the tie plate is provided with 40 a flat elevated face 7 which engages with a part of the underside of the base of the rail, said part extending transversely inward from the outer edge of the rail base to about three quarters of the width of said base.

45 Near the outer end of the tie plate the same is provided on its upper side with an inwardly projecting hook 8 which engages over the adjacent outer edge of the rail base for holding the rail down on the tie plate, 50 as shown in Figs. 1 and 2. At the inner end of the tie plate the same is provided on its upper side with a recess 9 which extends from one longitudinal edge of the tie plate to the other and which has its inner part arranged underneath about one quarter 55 of the width of the underside of the rail

base at the inner edge thereof while the outer part of said recess is arranged beyond the inner edge of the rail base. The inner longitudinal wall or side 10 of the recess 9 60 is undercut or beveled and the outer longitudinal wall 11 thereof is preferably vertical, as shown in Figs. 1 and 3.

The locking plate rests in the recess 9 and its inner end extends underneath the 65 inner part of the rail base and engages its upper side with the underside of the rail base while its outer part is arranged beyond the inner part of the rail base. The inner edge of the locking plate is beveled and en- 70 gages underneath the inner undercut wall of the recess and the outer end of the locking plate is vertical and engages with the corresponding wall of the recess. On the inner part of the locking plate the same is 75 provided on its upper side with an inwardly projecting hook 12 which engages over the inner edge of the base of the rail, as shown in Figs. 1 and 2, for holding this part of the rail down on the tie plate. The outer 80 edge of the tie plate is provided with openings 13 which receive the screws 5 whereby this end of the tie plate is secured to the tie. The inner end of the tie plate is provided within its recess with openings 15 and 85 the locking plate is also provided with openings 14 adjacent to its hook and in register with the openings 15 of the tie plate, each pair of openings 15, 14 of the tie and locking plates receiving one of the screws 6 for 90 securing the same to the tie and the rail.

In securing a rail to the tie the tie plate is first placed on the tie, then the rail is placed on the tie plate and engaged with the outer edge of its base under the hook of the tie 95 plate, then the locking plate is inserted in the recess of the tie plate so that part of the same projects under the inner edge of the rail base and the hook of the locking plate engages over the last mentioned edge 100 of the rail base. Inasmuch as the rail engages the greater part of its underside with the top of the tie plate the same is fully supported and need not be again raised or shifted to permit of inserting the locking plate 105 underneath the same, thereby facilitating the laying of the railway. By extending the inner end of the locking plate underneath the rail and interlocking the same with the tie plate the rail is held down on 110 the tie plate independently of the screws 6, thereby preventing the rail from becoming

loose and reliably holding the same in place. The tie plate and locking plate can both be made by rolling the metal, thereby enabling the same to be produced at comparatively low cost.

I claim as my invention:

1. A fastener for securing a rail to a tie comprising a tie plate adapted to rest on a tie and provided on its upper side with an elevated face which is adapted to engage with part of the underside of the rail base and with a recess arranged below another part of the rail base and also provided on its upper side adjacent to the outer end of said elevated face with an inwardly projecting hook which is adapted to engage over one edge of the rail base, a locking plate arranged in said recess and having its upper side engaging with part of the underside of the rail base and provided with an inwardly projecting hook which is adapted to engage over the other edge of the rail base, the inner side of said recess being undercut and the outer side being vertical and the inner end of the locking plate being beveled and engaging with the undercut side of said recess while the outer edge thereof is vertical and engages with the vertical outer side of the recess.
2. A fastener for securing a rail to a tie comprising a tie plate adapted to rest on a tie and provided on its upper side with an

elevated face which is adapted to engage with part of the underside of the rail base and with a recess arranged below another part of the rail base and also provided on its upper side adjacent to the outer end of said elevated face with an inwardly projecting fixed hook which is adapted to engage over one edge of the rail base, a locking plate arranged in said recess and having an inwardly projecting movable hook which is adapted to engage over the other edge of the rail base, an inner flange projecting inwardly from the movable hook into engagement with the inner side of said recess and an outer flange projecting outwardly from the movable hook into engagement with the outer side of said recess, the inner side of said recess being undercut and the inner end of the locking plate being beveled and engaging with the undercut side of said recess, and means for securing said tie plate and locking plate to the tie, comprising screws passing through the tie plate outside of the fixed hook and through the outer flange of the locking plate and the adjacent part of the tie plate.

Witness my hand this 4th day of November 1911.

AUGUST STILKE.
